UNITED STATES PATENT OFFICE.

JOHN ROSASSCO, OF HEALDSBURG, ASSIGNOR OF ONE-HALF TO JOSEPH CUNEO, OF SAN FRANCISCO, CALIFORNIA.

FRUIT-PITTING MACHINE.

SPECIFICATION forming part of Letters Patent No. 407,965, dated July 30, 1889.

Application filed September 21, 1888. Serial No. 286,026. (No model.)

To all whom it may concern:

Be it known that I, JOHN ROSASSCO, of Healdsburg, in the county of Sonoma, State of California, have invented an Improvement 5 in Fruit-Pitting Machines; and I hereby declare the following to be a full, clear, and exact description thereof.

My invention relates to that class of fruit-pitting machines in which the fruit rests upon 10 a properly apertured and slitted bed, and a vertically-movable spring-controlled punch provided with side knives or cutters is brought down upon the fruit, whereby its flesh is cut and its stone or pit is driven out through the 15 bed.

My invention consists in certain improvements in this class of machines and in the combination of parts hereinafter fully described.

20 Referring to the accompanying drawings, &c., Figure 1 is a perspective view of my fruit-pitting machine. Fig. 2 is a section of the base-plate.

A is the base-plate, having formed therein 25 a socket-seat *a*, having three beveled side flanges *a'* and a central aperture *a''*, with side slits *a'''*.

B is a rubber cushion having its edges beveled correspondingly to the flanges of the 30 socket-seat *a* and adapted to fit in said seat. In this cushion is made a central aperture *b*, with side slits *b'*, said aperture and slits corresponding with the aperture and slits in the seat *a*. Around the central aperture of the 35 cushion is a recessed seat *b''* for receiving the fruit.

C is a standard from which the guide-arms D project at right angles.

E is a bent rod having a long arm *e* and a 40 shorter arm *e'*, the lower end of which forms a punch, (represented by *e''*.) Both arms of the bent rod pass through and are guided in the arms D, while the longer arm also passes through the bed-plate A, and may have attached to its lower end a treadle-connection, 45 whereby the machine may be operated by the foot, if desirable.

F is a hand-lever, which is pivoted by pin *f* to the top of the bent rod E. The rear end 50 of this lever is fulcrumed at *g* in the upper

ends of the links G, the lower ends of which are pivoted to the back of the standard near its base. Said links thus form a fulcrum for the lever, and being themselves pivoted at their lower ends provide for the proper movement of the lever, so that it will direct its power to move the bent rod E perpendicularly. 55

H is a spring, here shown as made in two independent parts, one being on each side of and conforming to the general direction of the 60 upper portion of the links and the rear portion of the lever. The lower ends of the springs are attached fixedly to the upper end of the standard, while the upper ends are attached to the upper end of the bent rod E, 65 preferably upon the pin *f*, which pivots the lever to said rod.

The punch *e''* of the short arm of the rod is slitted, and into this slit is let and secured 70 the bent knife or cutter I, so that one-half of the knife passes downwardly on each side of and below the lower end of the punch.

The base or bed plate A of the machine is adapted to be screwed to the table, so as to hold it in proper position. 75

The operation is as follows: The fruit is placed on end within the recessed seat *b''* of the rubber cushion. The lever F is then forced down, so as to force down the bent rod E, which movement first brings the wings of the 80 knife I into contact with and cuts the flesh of the fruit, while the punch *e''* comes down on top of the pit and forces it downwardly through the central aperture of the cushion and of the socket-seat of the bed-plate, the slits in the 85 cushion and in the socket-seat of the bed-plate receiving the wings of the knife. When the lever is relieved, the spring returns the bent rod for the repetition of the operation. The rubber cushion being fitted to the base-plate, 90 as described, renders it easily removable to be cleaned and another substituted when desired. The recessed seat *b''* in the cushion provides for the proper holding of the fruit under operation. The bent winged knife I 95 properly cuts the flesh of the fruit, so that the pit or stone is sufficiently freed to be driven out without bruising the fruit.

The arrangement of spring as herein described is simple and effective, and is less lia- 100

ble to get out of order than the spiral spring encircling the rod, as has heretofore been customary. The lever-connection having the variable fulcrum is of advantage in providing a simple power device for imparting a perfectly vertical or perpendicular motion to the bent rod.

Having thus described my invention, what I claim as new, and desire to secure by Letters Patent, is—

An improved fruit-pitting machine consisting of the combination of a bed-plate having an apertured and slotted socket-seat with beveled surrounding flanges and a fixed stand-
ard with guide-arms, a cushion having beveled sides fitted in the socket-seat and having an aperture and side slits and a recess-seat for the fruit, a vertically-movable bent rod

fitted in the guide-arms of the standard and having one end slotted and provided with a punch, and a bent winged knife fitted in the slotted end of said rod and having its wings projecting below the punch, a lever pivotally connected with the top of the bent rod, links pivoted at their lower ends to the standard and at their upper ends to the rear end of the lever, and springs secured to the standard and to the top of the bent rod, substantially as described.

In witness whereof I have hereunto set my hand.

JOHN ROSASSCO.
